UNITED STATES PATENT OFFICE.

AMOS F. DIXON, OF NEWARK, NEW JERSEY, ASSIGNEE TO WESTERN ELECTRIC COMPANY, OF NEW YORK, N. Y., A CORPORATION OF ILLINOIS.

SWITCH-SELECTOR.

1,143,368.

Specification of Letters Patent. Patented June 15, 1915.

Application filed December 12, 1914. Serial No. 876,843.

To all whom it may concern:

Be it known that I, AMOS F. DIXON, a citizen of the United States, residing at Newark, in the county of Essex and State 5 of New Jersey, have invented a certain new and useful Improvement in Switch-Selectors, of which the following is a full, clear, concise, and exact description.

This invention relates to switch selectors 10 and more particularly it relates to a mechanism for selectively actuating a series of switches and suitable, for example, for use in a printing telegraph keyboard transmitter. Its object is to produce an improved 15 arrangement of parts for effecting such a switch selection.

In the embodiment of this invention hereby described, the switches to be selected have their movable contact members carried 20 on levers. These contact members are normally held in one position by biasing devices acting through the agency of other levers. Individual to each of the switches 25 is a tripping member, one or more of which may be brought into operative position by the actuation of one of the keys of the keyboard. There is also provided an actuating device for locking the selected tripping members in their operating positions, locking 30 the unselected tripping members against selection, and effecting the operation of the switches corresponding to the tripping members which have been selected.

This invention further provides a guard 35 for preventing the accidental actuation of the switches and for removing the selected tripping members from their locked engagement with the above mentioned actuating device, upon the deenergization of an elec- 40 tromagnet associated therewith.

Other features of the invention will appear in connection with the consideration of the accompanying drawings in which—

Figure 1 gives a plan view of the working parts of a keyboard transmitter employing the switch selector of my invention; Fig. 2 shows a vertical section of the transmitter as viewed from the front; Fig. 3 gives a sectional view along line 3—3 of Fig. 2; Fig. 4 shows in detail the operated 45 position of one of the switches, together

with its associated levers and tripping mechanism.

Referring in detail to the drawings, a keyboard similar in arrangement to that 55 of a typewriter is employed, the key levers 5 being provided at one end with button-shaped keys 6, and at the other end being pivoted to the supporting frame work 7 in any suitable manner. Each key lever 5 carries 60 one or more downwardly extending lugs 8 adapted upon the depressing of its key 6 to engage and depress one or more of the five bars 9, and the bar 10, which are located below the lever 5 and extend at right angles 65 thereto. Bars 9 and 10 are swung on a system of levers 11 and 12. Bars 9 are normally held in their upper position by springs 13 and bar 10 is similarly held by spring 14. The upper position of the bars 70 9 are determined by stop 15 which acts against levers 11, and the upper position of 10 is determined by stop 16. Pivoted to the upper ends of levers 11 are tripping fingers 20 having irregular shaped lugs 21, the 75 function of which will be hereinafter described.

Located at the left of the keyboard and above the tripping fingers 20 are the switches to be selected. These switches comprise the movable contact members 22 and the two sets of stationary contact points 23 and 24. Each contact member 22 is mounted on a lever 25 pivoted at 26, and is normally held in contact with point 23 by a spring 80 27 acting through the medium of another lever 28, which is pivoted at 29.

When a key lever 5 is depressed, certain 85 of the bars 9 will be selectively depressed, depending upon the number and position of 90 the lugs 8 on the said key lever. The lever 11 and tripping finger 20 of a selected bar 9 will thereupon be advanced into the position indicated by the dotted outline in Fig. 2. In moving forward into this position, 95 the rounded toe portion of lug 21 encounters the angular end 30 of guard 31 which is pivoted at 32 and normally held against stop 33 by spring 34. The function which guard 31 performs at this stage of the operation 100 is to prevent the finger 20 from being prematurely thrown against the end of lever

28. Furthermore, in the advanced position of the finger 20, the heel of the lug 21 drops down in front of the hammer bar 35, carried by the arms 36 which are in turn attached to the shaft 46 on which armature 37 of the electromagnet 38 is mounted. Finger 20 is in this position prevented by the engagement of lug 21 with hammer bar 35 from returning to its normal position.

10 Each of the key levers 5 in addition to depressing certain of the bar 9, depresses bar 10, thus moving extension 39 of lever 12 to the left and closing contact 40 which controls the energization of magnet 38. The 15 energization of this magnet causes it to attract armature 37, thereby raising the hammer bars 35 and forcing the fingers 20, which have been selected, upward against the ends of their corresponding levers 28, as 20 illustrated in Fig. 4. This action relieves levers 25 from the tension of springs 27, and contact members 22 are consequently drawn into contact with contact points 24 by springs 45. Those of the fingers 20 which 25 have not been selectively advanced by the depression of the key lever 5 in question, will however, be raised by the hammer 35 into a plane in which their ends lie opposite the ends of their respective levers 28 and 30 will be prevented by said lever ends from advancement in case any other key lever 5 should be depressed before the magnet 38 is deenergized. In the upward movement of 35 the fingers 20 the guard 30 is forced outward against the tension of spring 34 by the toe of lug 21 and snaps into a position beneath the lugs 21 as illustrated in Fig. 4. Guard 30 is thus in a position to disengage the lugs 21 from the hammer bar 35 when the latter 40 falls back to normal upon the deenergization of magnet 38, thereby allowing the fingers 20, levers 11, and bars 9 to be restored to normal by springs 13. It is thus seen that 45 any desired combination of switches depending upon the positioning of the lugs 8 on the key levers 5.

While the invention is herein shown as applied to a keyboard transmitter, it is obvious that it may be applied to various other uses without departing from its spirit and scope.

What is claimed is:

1. A switch selector comprising a plurality of switches, means for holding said switches in a normal position, tripping members, means for selectively bringing said members into operative position, and actuating means for locking said selected members in their selected position, and causing said selected members to release said holding means.

2. A switch selector comprising a plurality of switches, means for holding said switches in a normal position, tripping mem-

bers, means for selectively bringing said members into operative position, and actuating means for locking said selected members in their selected position, moving the unselected tripping members into a non-operative position, and causing said selected members to release said holding means.

3. A switch selector comprising a plurality of switches, means for holding said switches in a normal position, tripping members, means for selectively bringing said members into operative position, actuating means for causing said selected members to release said holding means, and a guard for preventing the accidental release of said holding means.

4. A switch selector comprising a plurality of switches, means for holding said switches in a normal position, tripping members, means for selectively bringing said members into operative position, actuating means for locking said selected members in their said operative position, moving the unselected tripping members into a non-operative position and causing said selected members to release said holding means, and a guard for preventing the accidental release of said holding means.

5. A switch selector comprising a plurality of switches, means for holding said switches in a normal position, tripping members, means for selectively bringing said members into operative position, locking said selected members in their selected positions, moving the unselected tripping members in a non-operative position and causing said selected members to release said holding means, an electromagnet for operating said actuating means, and circuit-closing means for energizing said electromagnet upon the selection of said tripping means.

6. A switch selector comprising a plurality of movable switch members, means for holding said members in a normal position, tripping members, means for selectively bringing said tripping members into operative position, actuating means for locking said selected tripping members in their selected positions and causing said selected members to release said holding means, an electromagnet for operating said actuating means, circuit-closing means for energizing said electromagnet upon the selection of said tripping means, and a guard for preventing the accidental release of said holding means.

7. A switch selector comprising a plurality of movable switch members, levers, means for holding said members in a normal position through the coöperation of said levers, tripping members, means for selectively bringing said members into operating position, actuating means for causing said

selected tripping members to destroy the co-operation of said levers, and means for changing the position of said switch members.

- 5 8. A switch selector comprising a plurality of movable switch members, lever arms, means for holding said members in a normal position through the co-operation of said lever arms, tripping members, means
10 for selectively bringing said members into

operating position, and actuating means for causing said selected tripping members to destroy the co-operation of said levers.

In witness whereof, I hereunto subscribe my name this 11th day of December A. D., 1914.

AMOS F. DIXON.
